Wesley G. Barr

ATTORNEY

UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

FEEDER-CABLE SUPPORT.

Application filed September 3, 1919. Serial No. 321,410.

To all whom it may concern:

Be it known that I, WILLIAM SCHAAKE, a citizen of the United States, and a resident of Pittsburgh, in the county of Allegheny and State of Pennsylvania, have invented a new and useful Improvement in Feeder-Cable Supports, of which the following is a specification.

My invention relates to conductor-supporting devices and particularly to such devices as are employed in supporting feeder conductors in mines and other places.

One object of my invention is to provide a device of the above indicated character that shall be simple and durable in construction, economical to manufacture and easy to manipulate.

Another object of my invention is to provide a conductor-supporting device that shall comprise a relatively-small number of simple interfitting parts that shall be held in position by a force exerted by a conductor supported thereby.

Another object of my invention is to provide a conductor-supporting device for mines or other places of restricted overhead, or other, space that shall be of substantially minimum dimensions, thereby conserving space and providing a neat and compact structure.

Heretofore, it has been usual, in certain conductor-supporting devices, to employ nuts, screws, bolts and other relatively complicated and expensive machined parts that are somewhat difficult to install. Some of these have, also, been so constructed as to occupy an excessive amount of space which, in mines or other places where space is limited, has been an objectionable feature thereof.

In practicing my invention, I provide a relatively simple structure of few parts, requiring a very small amount of machine work, that are of such simple interfitting relation as to greatly facilitate the manipulation thereof in installing and removing a conductor. The device is, also, of such compact construction as to occupy a substantially minimum amount of space, thereby improving conditions, and being a desirable device, in mines and other places of limited overhead space.

Figure 1 of the accompanying drawings is a view, partially in section and partially

in elevation, of a device embodying my invention, as viewed in the direction of a conductor, and Fig. 2 is an elevational view thereof taken at right angles to Fig. 1.

A member 1, preferably of metal, is provided with a body portion 2, for attachment to a suspension insulator 3 or other device, and substantially parallel legs or portions 4. Oppositely-disposed openings 5, adjacent the outer ends of the legs 4, receive a pin 6 extending between the legs 4.

A member 7, constituting a seat for a feeder cable or other conductor 8, also extends between the legs 4 and has openings 9 adapting it to be fitted over the outer ends of the legs 4. Offset portions 10, at the ends of the member 7, overlap the ends of the pin 6 and prevent the withdrawal of the latter.

During the operation of installing the conductor 8, and with the members 6 and 7 removed, the conductor is first placed between the legs 4 and is moved to a position relatively close to the body portion 2. This permits the member 7 to be placed over the legs 4 and moved beyond the openings 5, after which the pin 6 may be readily placed in position. The device being, as shown, in the vertical position, when the conductor 8 and the member 7 are released, the latter will assume the position shown in the drawings and be securely locked in place.

It will, of course, be understood that the same structure may be used in other positions wherein there is a force exerted by the conductor 8 against the member 7.

The several parts, being relatively loosely related, and the member 7 being thereby permitted to have a rocking movement about the pin 6, assure a good bearing engagement between the conductor 8 and the member 7.

While I have shown and described a particular form of my invention, changes may be effected therein without departing from the spirit and scope thereof, as set forth in the appended claims.

I claim as my invention:

1. A conductor-supporting device comprising a structure having substantially parallel portions, a readily-removable conductor seat member disposed between said portions and held against lateral displacement thereby, and a readily-removable holding member for supporting the seat member

2
disposed between the parallel portions and held against transverse movement by said seat member.

2. A conductor supporting device comprising a forked structure, a conductor seat disposed between the prongs of the forked structure and slideable longitudinally thereof, and a holding member disposed between the prongs of the forked structure and slideable transversely thereof for preventing removal of the conductor seat from the said prongs.

3. A conductor-supporting device comprising a supporting member having a receiving portion therein, a holding member in said receiving portion, and a conductor-seat member fitted over said supporting member and having a portion for preventing the removal of the holding member.

4. A conductor-supporting device comprising a supporting member formed to receive a holding member, a holding member therefor, and a member co-operating with the supporting member and the holding member to position a conductor and prevent the withdrawal of the holding member.

5. A conductor-supporting device comprising a supporting member, a holding

member and a member co-operating with the supporting member and the holding member to position a conductor and prevent the withdrawal of the holding member.

6. A conductor-supporting device comprising a forked member having oppositely disposed receiving portions in the legs thereof, a conductor-seat member extending between said legs and having portions through which said legs extend and a projection at each end, and a pin extending between, and into the receiving portion of, said legs, the projections on the seat member extending across the longitudinal axis of said pin to prevent the withdrawal of the pin.

7. A conductor-supporting device comprising two substantially parallel portions having oppositely-disposed receiving portions, a conductor-seat member co-operating with said parallel portions and having an offset portion at each end, and a pin extending between, and into the receiving portions of, said parallel portions, said offset portions being positioned to prevent the withdrawal of the pin.

In testimony whereof, I have hereunto subscribed my name this 25th day of Aug., 1919.

WILLIAM SCHAAKE.
